PROCESS FOR THE MANUFACTURE OF
ACETIC ACID FROM ACETALDEHYDE

Karl Wiesler, Constance, Germany, assignor, by
mesne assignments, to the firm of Deutsche
Gold- und Silber-Scheideanstalt vormals Roess-
ler, Frankfort-on-the-Main, Germany

No Drawing. Application January 27, 1930,
Serial No. 423,900. In Germany February 26,
1929

12 Claims. (Cl. 260—116)

It has been known for a long time that acetaldehyde can be oxidized to acetic acid by the action of air (see Liebig A. 14, 139). In carrying out this reaction in practice great difficulties 5 are caused as by the absorption of oxygen in acetaldehyde, first unsuitable intermediate products (either peracetic acid ($\text{CH}_3\text{COO.OH}$) or acetaldehyde peroxide ($\text{CH}_3\text{CHO.O}_2$)) are formed. The conversion of these intermediate products into 10 acetic acid takes place very vigorously. In treating large quantities dangerous explosions can, therefore, occur. For this reason various proposals have already been made to enable the oxidation of acetaldehyde to acetic acid to be 15 carried out on the commercial scale in a non-dangerous manner. Thus, for example, it has been proposed to add catalysts whose presence accelerates the decomposition of the peracetic acid. A further proposal consists in that by the 20 use of relatively high temperatures (about 100° C.) the dangerous accumulation of peracetic acid is counteracted, which precaution meanwhile entails the diminution of the yield (an increase in the formation of carbon dioxide), and further- 25 more is not absolutely reliable as, with accidental lowering of the temperature the peracetic acid is not destroyed.

It has been found that a dangerous accumulation of peracetic acid can be avoided with 30 security, and the oxidation of acetaldehyde to acetic acid on the commercial scale can be carried out in a simple and smooth manner if an excess of oxygen, or oxygen admixed with inert gases is used, such that the quantity of oxygen consider- 35 ably exceeds the quantity of oxygen required for the oxidation of the acetaldehyde to acetic acid.

The process can, for example, be carried out in such a manner that acetaldehyde is allowed to flow continuously into a mixing vessel and, at 40 the same time, the oxidizing gas or gas mixture, the quantity of which is so measured that the quantity of oxygen added is considerably higher than the quantity theoretically required for the oxidation of the inflowing acetaldehyde to acetic acid, is led in. Preferably, for example, quantities of oxygen are used which exceed the quantity theoretically required by about 50 per cent or more.

The oxidation can be carried out at tempera- 50 tures between 55 and 80° C. Temperatures mostly between 60 and 75° C. have been shown to be particularly advantageous. At these temperatures only a very little carbon dioxide is formed so that the formation of acetic acid proceeds with better yields.

When working in apparatus with large average quantities the excess heat of reaction is preferably conducted away by indirect cooling, for example in such a manner that a cooling apparatus is built in, or immersing the whole mixing vessel in a cooling bath. The production output can be increased by good mechanical mixing. The mixing can, for example, be effected by means of stirrers built into the mixing vessel, or for example in such a manner that acetaldehyde and oxidation gas are passed through turbo-mixers or other suitable mixing devices, or if desired through several consecutive turbo-mixers.

In using higher pressures the oxidation generally proceeds in the same manner as at atmospheric pressure; on the other hand the acetaldehyde is more completely converted, so that by use of excess pressure, smaller absorption apparatus can be used for recovery of the unaltered acetaldehyde. Also, the absorption of the unaltered acetaldehyde can be improved by the use of higher pressures. The working pressure does not need to considerably exceed atmospheric pressure. Pressures of about 1.5 atmospheres have been proved to be suitable. With continuous working methods it is preferable to carry out the procedure in such a manner that the waste gas, after passing the absorption apparatus, is passed through a pressure regulator. The pressure regulation can be carried out in a simple and reliable manner, 70 for example by passing the waste gas from the bottom into a vessel of the wash-bottle type which is filled with water, to a predetermined height according to the degree of excess pressure desired.

In working in accordance with the invention, 75 the reaction starts immediately. The formation of acetic acid proceeds smoothly and so rapidly that the operation can be carried out with high average quantities, that is to say in a given apparatus high production yields can be obtained. 80 The peracetic acid concentration never exceeds, as has been found, a few tenths per cent, so that dangerous accumulations of this body are obviated.

The high velocity of flow ensures at the same 85 time particularly favourable reaction conditions, on the one hand that the rapid gas stream extraordinarily improves the mixing, and on the other hand that the effective limiting surface between the gas and liquid is particularly large. 90 The process can also be carried out with the co-operation of oxygen carriers of known type. The reaction-promoting action of the high oxygen concentration, together with the large gas velocity, however enables the treatment of such 95 100 105 110

large working quantities that oxygen carriers can be omitted entirely, but also the addition of particular catalysts for the destruction of the peracetic acid is unnecessary as, as already mentioned, appreciable peracetic acid concentrations do not occur.

A further advantage of the process consists in that the temperatures can be so selected that the most favourable course of reaction is obtained. 10 It is, for example, not necessary (as has been effected in some processes) to keep the temperature at the beginning of the oxidation below a definite limit by carefully supervised cooling or addition of oxygen and only to allow it to increase gradually. It is also not necessary (as has been effected in other processes) to maintain a high temperature, likewise to be exactly supervised, in definite parts of the apparatus, in order to decompose the peracetic acid. Furthermore, in operating according to the present invention, the temperature can be kept unaltered during the whole of the continuous process, so that after once regulating the velocity of flow and the cooling the supervision is extremely simple.

The temperature can thus be so adjusted and kept at such a degree as is most favourable for the absorption of oxygen, or for the formation of acetic acid (lower temperatures, as is known, 30 reduce the reaction velocity, that is to say reduce the yield of production whilst higher temperatures again entail too extensive oxidation, and therefore influence the yield).

The large quantity of gas introduced into the process according to the invention also supports the maintenance of the desired reaction temperature, firstly in that the reaction product withdraws direct heat from the vapours introduced with it and, further, that the heat exchange 40 through the walls of the cooling device is favoured by the high gas velocity and the energetic movement of the liquid.

The further treatment of the reaction product can be effected in the usual manner. The liquid 45 reaction product about 95 per cent acetic acid with small contents of acetaldehyde can, for example, be subjected to a rectification whereby, after short running, acetic acid is obtained direct. The waste gases can be passed through 50 cooling and absorbing devices in order to recover the acetaldehyde vapours carried with them. For absorption a wash-tower sprinkled with water or acetic acid as a washing liquid, can for example be used. Preferably the crude reaction product 55 is used as an absorption agent. This contains some acetaldehyde; at the low temperatures in the washer it is capable, however, of absorbing still further considerable quantities of acetaldehyde.

60 The acetaldehyde residues which then still remain in the waste gas can be washed out with acetic acid freed from acetaldehyde but not rectified, or with water, if desired, with consecutive use of the said absorption agents. Much distillation work is saved by treating in this manner, and the absorption proceeds substantially more simply and more economically. This method of operation also enables the use of suitably large 65 quantities of absorption liquid without thereby incurring increased rectification costs. With the use of large quantities of absorption agents the desired washing action is obtained with a smaller absorption apparatus, which is of great advantage for the economy of the process. Wash tow-

ers with filling bodies, or other gas absorption apparatus can be used as absorption devices.

Examples

1. In a mixing vessel 79.2 kg. of acetaldehyde and 170 cu. m. of air were introduced per hour. The mixing vessel was provided with a stirrer and with a cooling coil. The temperature was maintained at about 70° C. The reaction product was cooled down and partially used for spraying, the absorption towers. The waste gases were cooled, and washed in the absorption tower consecutively with the liquid reaction product, and then with reaction product freed from acetaldehyde, and finally with water. The unaltered acetaldehyde of about 8.3 kg. per hour (10.4% of the quantity used) was recovered from the absorption agent by distillation and again introduced to the oxidation.

An acetic acid of about 95% strength was obtained with a yield of 97% of the theoretical amount. The production yield amounted to 2250 kg. of acetic acid daily.

2. In an apparatus the capacity of which was one-twentieth of that used according to Example 100 1, 10.15 kg. of acetaldehyde and 9 cu. m. of an oxidizing gas consisting of 50% oxygen and 50% nitrogen, were introduced per hour into a mixing vessel. The mixing vessel was provided with a stirrer and a cooling jacket. The method of working was the same as that described in Example 1. 3.9% of acetaldehyde (about 0.4 kg. per hour) were again recovered unaltered and again returned to oxidation. A 96% acetic acid with a yield of 98% of the theoretical amount 110 was obtained, the yield of production amounted to 313 kg. of acetic acid per day.

From the examples it can be seen that the yield is substantially greater with the use of oxidizing gases rich in oxygen. Calculated on 115 the same volume with the use of an oxidizing gas containing 50% oxygen instead of air, there is obtained nearly three times the production yield.

I claim:—

1. In a process for the continuous production of acetic acid by oxidation of acetaldehyde in the liquid phase with oxygen, the step which consists in continuously introducing at the same time acetaldehyde in the liquid phase and a considerable excess of oxygen into the reaction vessel at temperatures between 55° and 80° C. so that there is continuously present more oxygen than is required for oxidation of all the acetaldehyde, while causing intimate contact between the acetaldehyde and the oxygen said oxygen being present in such an excess amount that the waste gases evolved in the reaction contain free oxygen.

2. A process according to claim 1 in which the intimate contact is produced by mechanical mixing.

3. A process according to claim 1 consisting in carrying out the oxidizing process at an absolute pressure of substantially 1.5 atmospheres.

4. A process according to claim 1 consisting in 140 treating the waste gases from the acetic acid formation process with acetic acid for the purpose of recovering acetaldehyde.

5. A process according to claim 1 consisting in treating the waste gases with acetic acid at an 145 increased pressure of substantially 1.5 atmospheres absolute.

6. A process as set forth in claim 1 which consists in introducing continuously into the reaction vessel a quantity of oxygen which is at least 150

- one and one-half times that quantity of oxygen which is necessary for the oxidation of all the acetaldehyde present in said reaction vessel, so that there is continuously present an oxygen excess of at least 50% over the amount theoretically necessary for the reaction. 5
7. Process for the uninterrupted production of acetic acid consisting in continuously introducing acetaldehyde in the liquid phase into a mixing vessel, and at the same time continuously introducing oxygen in quantities which considerably exceed the quantities theoretically required for the oxidation of all the inflowing acetaldehyde to form acetic acid while causing intimate contact 10 between the acetaldehyde and the oxygen, the oxygen being present in such excess that the effluent waste gases issuing from the mixing vessel contain free oxygen. 15
8. A process for the uninterrupted production of acetic acid, consisting in continuously introducing acetaldehyde in the liquid phase into a mixing vessel, simultaneously, continuously introducing oxygen in quantities which considerably exceed the quantities theoretically required for the oxidation of all the inflowing acetaldehyde to acetic acid while causing intimate contact between the acetaldehyde and the oxygen, the quantity of oxygen being present in such excess that the waste gases evolved in the reaction contain 20 free oxygen, and then passing the said waste gases through cooling and absorption devices for the purpose of recovering unaltered acetaldehyde. 25
9. A process for the uninterrupted production of acetic acid consisting in continuously introducing acetaldehyde in the liquid phase into a mixing vessel simultaneously, continuously adding oxygen in quantities considerably exceeding those required for the oxidation of all the inflowing acetaldehyde to acetic acid while causing intimate contact between the acetaldehyde and the oxygen, the quantity of oxygen being present in such excess that the effluent waste gases contain free oxygen, and then treating the said waste gases with unrectified acetic acid formed in the reaction vessel, for the purpose of recovering the acetaldehyde. 30
10. A process for the uninterrupted production of acetic acid, consisting in continuously introducing acetaldehyde in the liquid phase into a mixing vessel, simultaneously, continuously adding oxygen in quantities considerably exceeding the quantities theoretically required for the oxidation of all the inflowing acetaldehyde to acetic acid while causing intimate contact between the acetaldehyde and the oxygen the quantity of oxygen being present in such excess that the effluent waste gases contain free oxygen, and then treating the said waste gases first with unrectified acetic acid and then with rectified acetic acid for the purpose of recovering acetaldehyde. 35
11. A process for the uninterrupted production of acetic acid, consisting in continuously introducing acetaldehyde in the liquid phase into a mixing vessel, simultaneously, continuously adding oxygen in quantities considerably exceeding the quantities theoretically required for the oxidation of all the inflowing acetaldehyde to acetic acid while causing intimate contact between the acetaldehyde and the oxygen, the quantity of oxygen being present in such excess that the effluent waste gases contain free oxygen, and then 40 treating the said waste gases first with acetic acid for the purpose of recovering acetaldehyde and then with aqueous liquids for the purpose of removing acetic acid. 45
12. A process for the uninterrupted production of acetic acid consisting in continuously introducing acetaldehyde in the liquid phase into a mixing vessel, and at the same time continuously introducing oxygen in quantities which considerably exceed the quantities theoretically required for the oxidation in the liquid phase of all the inflowing acetaldehyde to form acetic acid, while causing intimate contact between the acetaldehyde and the oxygen the quantity of oxygen being supplied in such excess that free oxygen is 50 present in the waste gases issuing from the mixing vessel. 55
